Inventor

UNITED STATES PATENT OFFICE.

CLAUDE A. HERMAN, OF STRATFORD, CONNECTICUT.

ELECTRIC DRIVE.

Application filed October 31, 1927. Serial No. 230,006.

This invention relates to an electric drive for flexible shafts or the like, and particularly to a portable drive for this type of mechanism, and has for an object to provide a simple and rigid structure for carrying the motor and the counter shaft so that they are always maintained in proper relation and the counter shaft may be easily and quickly adjusted toward and from the motor shaft 10 for drives of different speed ratios.

It is also an object of the invention to provide a structure of this character having an improved bearing means to facilitate transportation of the drive from one location to 15 another.

With the foregoing and other objects in view, I have devised an electric drive, the preferred form of which is illustrated in the accompanying drawing, forming a part 20 of this specification. In this drawing,

Fig. 1 is a front elevation of the device, a portion of the base or standard being broken away.

Fig. 2 is a top plan view of the device with 25 a portion of the yoke broken away to show the catch, and

Fig. 3 is an end elevation but with the drive pulleys shown in dotted lines.

This device comprises an electric motor 30 including a housing 10 and having a rotary drive shaft 11. This motor is mounted on a base 12 which is preferably swiveled on a stand 13. This stand has three legs 14 to rest on the floor or any suitable support as a 35 bench, and the base is swiveled to this stand by the central swivel stud 15 so that the motor and the shaft operated thereby may be turned about an upright axis.

The device also includes a yoke 16 which 40 forms a convenient means for carrying the device and also carries the adjustable counter shaft. This yoke as shown is of substantially inverted U-shape with its side members or arms 17 and 18 secured to the opposite sides 45 of the motor housing 10, as for instance by screws 19, and it extends sufficiently above the housing to carry a support 20 for a counter shaft 21 running substantially parallel with the motor shaft, and the connecting bar 50 for the yoke is shaped to form a handle 22 above the counter shaft support. The counter shaft support is pivoted or hinged to the arm 17 as shown at 23, and extends across the yoke above the housing to the other arm 55 18 and projects forwardly therefrom to provide a handle 24. The forward portion of

this support has a recess 39 for the guide portion 40 of the yoke and this portion is held in the recess by a cap 41. Thus the counter shaft support is guided by the yoke in its 60 up and down movements and held against lateral movements and the lateral strains on the shaft support are not all carried by its hinge connection to the yoke. The support carries suitable bearings 25 for the counter 65 shaft which are spaced forwardly from the hinge 23 so that as the forward end of this support is swung up and down by the handle 24 the counter shaft is moved from and toward the motor shaft, as indicated in dotted 70 lines, Fig. 3. The arm 18 of the yoke and the support 20 are provided with any suitable type of cooperating means for retaining the support in different elevated positions. That shown comprises a catch lever 26 pivoted to 75 the support and operating a spring pressed pin 27 whose inner end may project into different openings 28 in the arm of the yoke. However, any suitable type of catch means 80 may be used if desired.

The counter shaft may be connected by means of suitable detachable means 29 to a flexible shaft 30 for driving any suitable type of portable tool, and this counter shaft is driven from the motor shaft by any suitable 85 type of drive. In the present arrangement the counter shaft and the motor shaft are each provided with cone grooved pulleys 31 and 32 connected by means of a round belt 33. The pulleys, of course, are reversed as 90 shown, so that by shifting the belt to different pulleys different speed ratios may be secured between the two shafts, and the up and down swinging movement of the counter shaft support 20 permits of easy shifting of the belt 95 and the placing of the counter shaft to give a proper tension on the belt.

At the rear of the motor is also mounted a supporting block 34 for carrying the electric socket and switch 35 which is connected 100 through a lead cord 36 to the motor. The socket may be connected by any usual type of plug 37 and flexible lead 38 to any suitable type of outlet receptacle from a source of electric current supply.

It will be apparent from the foregoing description that this arrangement provides a very simple, rigid structure which may be easily carried from place to place, and that the mounting for the counter shaft always 110 retains it in proper relation to the motor shaft to secure the proper driving. Also this

counter shaft may be easily and quickly shifted for shifting the belt and giving different driving speed ratios. The device is also universal so that the motor may be swung to any desired position for proper and effective operation of the flexible shaft and the tool driven thereby.

Having thus set forth the nature of my invention, what I claim is:

10. 1. In an electric drive, a motor including a housing and a rotary drive shaft, a yoke extending on the opposite sides of the housing and secured thereto and extending over the top of the same where it is shaped to form a handle above the housing, a support hinged to one side of said yoke to swing up and down, a counter shaft mounted in said support, cooperating means on the support and the other side of the yoke to retain the support and shaft at different elevations, and driving connection between the motor and counter shafts.
15. 2. In an electric drive, a motor including a housing and a drive shaft, an inverted substantially U-shaped yoke having its arms on the opposite sides of the housing and secured thereto and its connecting bar forming a handle over the housing, a shaft support hinged to one arm of said yoke and extending across to the other arm, cooperating means carried by the latter arm and the support to retain the support in different positions, a counter shaft mounted on the support, and a driving connection between the motor and counter shafts.
20. 3. In an electric drive, a motor including a housing and a drive shaft, uprights on opposite sides of the housing and secured thereto, a shaft support pivoted to one of said uprights to swing toward and from the motor, cooperating means on the support and the

other upright to retain the support in different positions with respect to the motor, a counter shaft mounted on the support, and a driving connection from the motor shaft to 45 the counter shaft.

4. In a portable electric drive, a motor including a housing and a drive shaft, a counter shaft substantially parallel with the motor shaft, a support for the counter shaft 50 connected with the housing and having a handle extending over the housing for carrying, means for shifting the counter shaft toward and from the motor shaft, and a driving connection between the two shafts. 55

5. In a portable electric drive, a motor including a housing and a drive shaft, a support pivotally mounted with respect to the motor, a counter shaft mounted on the support substantially parallel with the drive shaft and 60 spaced laterally from said pivot, means for swinging the support on its pivot to move the counter shaft toward and from the drive shaft, means for securing the support in different adjusted positions, and a drive connection between the two shafts. 65

6. In an electric drive, a motor including a housing and a drive shaft, a yoke having arms on opposite sides of the housing and connected therewith and a connection between said arms over the motor forming a handle, a support pivoted to one of said arms and extending across to the other arm, said latter arm and the support being provided with cooperating guide means to guide the support for vertical swinging movements about its pivot, means for securing the support in different adjusted positions, a counter shaft mounted on the support, and a drive connection between the two shafts. 70 75 80

In testimony whereof I affix my signature.
CLAUDE A. HERMAN.
